COMBINATION TOOTH PASTE TUBE AND
TOOTHBRUSH

José A. Lajara Torres, Utuado, P. R.

Application June 24, 1947, Serial No. 756,737

5 Claims. (Cl. 132—84)

1

My invention relates to tooth brushes, and more particularly to a tooth brush combined with a tooth paste tube.

The object of my invention is to provide a tooth brush and a tooth paste container combination wherein the tooth brush is pivotally mounted on said container.

Another object of my invention is to provide a tooth brush and a tooth paste container combination wherein the tooth brush is movable to a position in which it can receive tooth paste expelled from the mouth of the container or to a position wherein a portion of the tooth brush closes the mouth of the container and the container serves as a handle for the tooth brush in brushing the teeth.

Other objects of my invention may appear in the following specification describing my invention with reference to the accompanying drawings illustrating a preferred embodiment of my invention.

It is, however, to be understood, that my invention is not to be limited or restricted to the exact construction and combination of parts described in the specification and shown in the drawings, but that such changes and modifications may be made which fall within the scope of the claims appended hereto.

In the drawings:

Figure 1 is a longitudinal section taken through the illustrated device on the line 1—1 of Figure 3, the tooth brush being shown partly in elevation and partly in section.

Figure 2 is a top plan view of Figure 1.

Figure 3 is a sectional view taken on line 3—3 of Figure 1.

Figure 4 is a sectional view taken on line 4—4 of Figure 1.

Referring in detail to the drawings, the illustrated device comprises a container 10 having a substantially cylindrical shape, having a reduced nozzle 11 on its forward end. The container has a narrow slot 12 formed through its top and extending along the major portion of the length of the container, starting adjacent the closed rear end 13 of the container and extending to a point close to the front end.

Adjacent the forward end of the container a diametrically extending narrow support wall 14 is provided connecting the circumferential top and bottom wall portions 15 and 16, respectively, of the container. The forward surface 17 of the wall 14 is substantially semi-circular.

A channel 18 is formed in the wall of the container approximately centrally of the thickness 55

2

thereof. This channel starts at the same point at the rear end of the container at which the slot 12 starts and extends forwardly through the supporting wall 14, running parallel to the semi-circular forward end of said wall, and continues through the lower portion of the wall of the container 10 to a point diametrically opposite to the start of the channel 18 in the upper wall portion of the container.

10 A substantially cylindrical piston 19 fits slidably in the container and is provided with a lug 20 extending upwardly through the slot 12. A knurled hand grip 21 is formed on the outer end of said lug so that the piston 19 can be moved 15 axially in the container 10.

In the above described channel 18 a flexible ribbon 22 is slidably confined and has one end secured to and extending forward from the lug 20 on the piston 19. The other end of the ribbon 22 extends through an upwardly facing opening 23 provided at the rear end of the channel 18 in the lower wall portion of the container 10 and is connected to the rearward side of the lug 20, so that the ribbon 22 will travel through the 25 channel 18 when the piston 19 is moved forwardly or rearwardly in the container 10.

The container is filled through the nozzle 11 with tooth paste under pressure with the piston 19 positioned at its rearmost position in the container 10, as shown in Figure 1. The ribbon 22 prevents the tooth paste from extruding through the slot 12 in the container.

The forward portion of the container wall is approximately one-half as thick as the rest of the container wall and is formed in its outside surface with two longitudinal grooves 23' which are arranged diametrically opposite to each other and at a circumferential distance of 90° on the container wall from the slot 12.

25 The tooth brush 24 has a conventional head 25 with which a plurality of bristle tufts 26 are connected. Instead of the usual tooth brush handle a semi-cylindrical part 27 is formed on the rearward end of the head 25. Each rearward upper corner of the semi-cylindrical handle part 27 has a pin 28 fitting slidably in the grooves 23' in the container wall, so that the brush 24 is attached to said container 10 removably, slidably and pivotally.

On the inner surface of the handle part 29 directly adjacent to the brush head 25 is a semi-globular projection 30 fitting the opening of the nozzle 11. Surrounding the semi-globular projection 30 is a circular flat surface 31 adapted to engage the forward end of the nozzle 11. The inner

surface of the handle part 29 is shaped so that it will abut the outer surface of the nozzle 11 when the brush 24 is moved into nozzle closing and operative position by sliding the brush 24 forwardly in the grooves 23' from the position shown in full lines in Figure 1 and pivoting the brush upwardly and forcing the semi-globular projection 30 into the opening of the nozzle 11.

When the tooth paste is to be deposited on the brush bristles 26 the brush is pivoted downwardly from the dotted line position shown in Figure 1 and slid rearwardly in the grooves 23' to the full line position shown in Figure 1. Then the piston 21 is moved forwardly so as to expel a desired amount of tooth paste onto the bristles 26 arranged below the nozzle 11. After that the brush is returned into nozzle closing and operative position, shown in dotted lines in Figure 1, wherein the container 10 serves as a handle in brushing the teeth.

Having described my invention, I claim as new and desire to secure by Letters Patent:

1. The combination comprising an elongated tooth paste container closed at its rearward end and formed with an open nozzle on its forward end, a tooth brush comprising a brush head and a rearwardly extending handle part, said tooth brush being positioned longitudinally of said container with said brush head forwardly of said nozzle and with said handle part lying along said container, said tooth brush having a nozzle closing portion, said handle part having laterally spaced portions positioned at opposite sides of said container having laterally inwardly projecting pins pivotally and slidably engaging in longitudinal slots formed in opposite sides of said container whereby said tooth brush can be moved longitudinally and laterally relative to said container from a position in which said tooth brush is angulated with respect to said container and said nozzle is exposed to deposit tooth paste upon said brush head to a position in which said tooth brush is longitudinally aligned with said container and said nozzle closing portion of said toothbrush closes said nozzle, and wherein said container serves as a handle for said tooth brush.

2. The combination comprising an elongated tooth paste container closed at its rearward end and formed with an open nozzle on its forward end, a tooth brush comprising a brush head and a rearwardly extending handle part, said tooth brush being positioned longitudinally of said container with said brush head forwardly of said nozzle and with said handle part lying along said container, said tooth brush having a nozzle closing portion, said handle part having laterally spaced portions positioned at opposite sides of said container having laterally inwardly projecting pins pivotally and slidably engaging in longitudinal slots formed in opposite sides of said container whereby said tooth brush can be moved longitudinally and laterally relative to said container from a position in which said tooth brush is angulated with respect to said container and said nozzle is exposed to deposit tooth paste upon said brush head to a position in which said tooth brush is longitudinally aligned with said container and said nozzle closing portion of said toothbrush closes said nozzle, and wherein said container serves as a handle for said tooth brush, said container being formed with a longitudinal channel opening through a sidewall thereof, a piston in said container having a finger piece projecting outwardly through said channel whereby tooth paste present in said container can be ex-

pressed from said nozzle onto said brush head by moving said finger piece forwardly in said channel while holding said container and said brush stationary with said brush in the first mentioned position.

3. The combination comprising an elongated tooth paste container closed at its rearward end and formed with an open nozzle on its forward end, a tooth brush comprising a brush head and a rearwardly extending handle part, said tooth brush being positioned longitudinally of said container with said brush head forwardly of said nozzle and with said handle part lying along said container, said tooth brush having a nozzle closing portion, said handle part having laterally spaced portions positioned at opposite sides of said container having laterally inwardly projecting pins pivotally and slidably engaging in longitudinal slots formed in opposite sides of said container whereby said tooth brush can be moved longitudinally and laterally relative to said container from a position in which said tooth brush is angulated with respect to said container and said nozzle is exposed to deposit tooth paste upon said brush head to a position in which said tooth brush is longitudinally aligned with said container and said nozzle closing portion of said toothbrush closes said nozzle, and wherein said container serves as a handle for said tooth brush, said container being formed with a longitudinal channel opening through a sidewall thereof, a piston in said container having a finger piece projecting outwardly through said channel whereby tooth paste present in said container can be expressed from said nozzle onto said brush head by moving said finger piece forwardly in said channel while holding said container and said brush stationary with said brush in the first mentioned position, a flexible ribbon confined for longitudinal sliding movement in said channel in front of said piston, said ribbon being connected to said finger piece to move with said piston to close said channel in front of said piston to prevent escape of tooth paste from said container through said channel.

4. The combination comprising an elongated tooth paste container closed at its rearward end and formed with an open nozzle on its forward end, a tooth brush comprising a brush head and a rearwardly extending handle part, said tooth brush being positioned longitudinally of said container with said brush head forwardly of said nozzle and with said handle part lying along said container, said tooth brush having a nozzle closing portion, said handle part having laterally spaced portions positioned at opposite sides of said container having laterally inwardly projecting pins pivotally and slidably engaging in longitudinal slots formed in opposite sides of said container whereby said tooth brush can be moved longitudinally and laterally relative to said container from a position in which said tooth brush is angulated with respect to said container and said nozzle is exposed to deposit tooth paste upon said brush head to a position in which said tooth brush is longitudinally aligned with said container and said nozzle closing portion of said toothbrush closes said nozzle, and wherein said container serves as a handle for said tooth brush, said handle part being concaved to conformably embrace and lie closely along said container in the second mentioned position of said tooth brush.

5. The combination comprising an elongated tooth paste container closed at its rearward end and formed with an open nozzle on its forward

end, a tooth brush comprising a brush head and a rearwardly extending handle part, said tooth brush being positioned longitudinally of said container with said brush head forwardly of said nozzle and with said handle part lying along said container, said tooth brush having a nozzle closing portion, said handle part having laterally spaced portions positioned at opposite sides of said container having laterally inwardly projecting pins pivotally and slidably engaging in longitudinal slots formed in opposite sides of said container whereby said tooth brush can be moved longitudinally and laterally relative to said container from a position in which said tooth brush is angulated with respect to said container and said nozzle is exposed to deposit tooth paste upon said brush head to a position in which said tooth brush is longitudinally aligned with said container and said nozzle closing portion of said toothbrush closes said nozzle, and wherein said container serves as a handle for said tooth brush, said container being formed with a longitudinal channel including a first portion extending along one sidewall thereof and opening through said one sidewall and a second portion extending along an opposite sidewall, a piston in said container

10 having a finger piece projecting through said first channel portion whereby said piston can be manually moved forwardly to expel tooth paste present in said container from said nozzle onto said tooth brush head, and a continuous flexible ribbon slidably confined in said channel portions and connected to said finger piece whereby said ribbon closes said first channel portion in front of said piston to prevent escape of tooth paste from said container through said first channel portion.
